CLAIM

The ornamental design for a glider bench, as shown and described.

DESCRIPTION

FIG. 1 is a perspective view of a glider bench in accordance with a preferred embodiment of the present invention; FIG. 2 is a front view of the glider bench shown in FIG. 1; FIG. 3 is a back view of the glider bench shown in FIG. 1; FIG. 4 is a left side view of the glider bench shown in FIG. 1, with the right side view being a mirror image thereof; FIG. 5 is a top view of the glider bench shown in FIG. 1; and, FIG. 6 is a bottom plan view of the glider bench shown in FIG. 1.

The broken lines shown in the figures are for illustrative purposes only and form no part of the claimed design.
